UNITED STATES PATENT OFFICE.

EDMUND C. BATES, OF ALLIANCE, OHIO.

LIFTING-JACK.

1,189,778.

Specification of Letters Patent. Patented July 4, 1916.

Application filed January 16, 1914. Serial No. 812,583.

To all whom it may concern:

Be it known that I, EDMUND C. BATES, a citizen of the United States, residing at Alliance, in the county of Stark and State 5 of Ohio, have invented certain new and useful Improvements in Lifting-Jacks, of which the following is a specification.

The invention relates to lifting jacks of the character usually employed for raising 10 the axles of automobiles and other like vehicles; and the object of the improvement is to provide a lifting jack of comparatively small height and extensibility, which can be used under the different axles of the 15 same vehicle which are located at different heights from the supporting surface.

The general object of the invention is attained by providing a rest on the upper end 20 of the rack of the jack for raising the higher axle, and extending downward therefrom external to the base, to a connection with the lower end of the rack, a bracket upon which is provided another rest for raising the lower axle of the vehicle.

A further object of the improvement is to 25 provide means for adjusting the supplemental rest so that the same may be placed in different positions on the bracket without removing and returning any screws, bolts or other fastening means.

The several objects of the invention, thus 30 set forth in general terms, are attained by the construction and arrangement illustrated in the accompanying drawing forming part hereof, in which,

Figure 1 is a side elevation of the improved rack; Fig. 2, a vertical section of the same; and Fig. 3, a perspective view of the supplemental rest.

Similar numerals refer to similar parts 40 throughout the drawings.

The base 1 of the jack is provided with the vertical guide-way 2, in which is located and operated the rack 3, which is 45 raised and lowered by the usual mechanism shown collectively at 4 by means of a handle, the socket 5 of which is provided with a suitable extension, not shown. One side of the base is provided with the vertical 50 slot 6, the edge flanges of which form a suitable bearing or guide for the abutting side of the rack extending to the bottom of the base; and the upper end of the rack is provided with the rest 7, which is used 55 for raising axles and other objects nor-

mally located above the upper end of the base of the jack.

The bracket 8 is formed or secured on one side of the rest 7 and extends directly downward outside the corresponding wall 9 of the base of the jack, to a point opposite the lower end of the rack; and upon the lower end of the bracket is provided the lateral post or bar 10 which extends through the slot 6 in the wall 9 of the jack and is secured to or connected with the lower end of the rack. The supplemental rest 11 is provided on the bracket 8 for use in lifting axles or other objects normally located below the upper end of the base; and as shown this rest is adjustable upward and downward on the bracket 8, but such adjustment of the supplemental rest is not essential to the improvement in its broader features. For a ready adjustment of the supplemental rest 11, its inner end is provided with the bail or loop 12 adapted to engage around the bracket 8, and upon its lower side is provided the dependent detent 13 which is curved inward and adapted to engage in one of the sockets 14 formed by the series of teeth or lugs 15 on the outer side of the bracket 8. By this construction and arrangement it is evident that the bracket 8 which carries the supplemental rest is secured not only at its upper end but at its lower end with the rack 3, and that it has no contact or dependence whatever upon the base 1, excepting only that the lateral bar 10 extends through the slot 6 and acts as a stop for the rack at the upper end of the slot.

I claim:

A lifting jack including a base having a vertical guide way therein with a vertical slot having edge flanges extending to the bottom of the base in one side wall thereof, a rack located and operable in the guide way and bearing on the edge flanges of the slot, a rest on the upper end of the rack, a bracket extending downward from the rest external to the base and having a lateral bar on its lower end extending through the slot and connected with the lower end of the rack, and an adjustable supplemental rest on the bracket.

EDMUND C. BATES.
